UNITED STATES PATENT OFFICE

ADOLF STEFFEN, OF PITTSBURGH, PENNSYLVANIA, ASSIGNOR TO ADAMS BROS. MFG. CO., INC., OF PITTSBURGH, PENNSYLVANIA, A CORPORATION OF PENNSYLVANIA

DESIGN FOR A RADIANT HEATER

Application filed March 28, 1931. Serial No. 39,280. Term of patent 3½ years.

To all whom it may concern:

Be it known that I, ADOLF STEFFEN, a citizen of the United States, residing at Pittsburgh, Pennsylvania, post-office address number 1500 North Avenue West in the said city, have invented a new, original, and ornamental Design for Radiant Heaters, of which the following is a specification, reference being had to the accompanying drawing forming a part thereof.

The drawing represents a perspective view of a heater showing my new design.

I claim:

The ornamental design for a radiant heater as shown.

ADOLF STEFFEN.
